UNITED STATES PATENT OFFICE

2,459,213

CLOTH CLIP

Robert A. Bellamy, Oklahoma City, Okla.

Application June 9, 1947, Serial No. 753,488

5 Claims. (Cl. 24—253)

1

This invention relates to cloth holding clamps and is directed particularly to improvements in clamps or securing devices designed for use in holding a press cloth in position upon the presser face of the presser head of a pressing or ironing machine.

Clamps or holding devices of the character at present employed are not entirely satisfactory for the reason that they will frequently release the edge of the cloth when any unusual pull is applied thereto or if the clamp should be struck or bumped by the operator or in any other manner.

An object of the present invention is to provide a clamp which is designed in a novel manner which will prevent any accidental releasing of the cloth and which requires the application of force in two successively applied directions in order to open or disengage the clamp for the release of the cloth.

Another object of the invention is to provide a clamp of the character above described which will function satisfactorily to secure the cloth tightly in position but which, at the same time, is designed in a simple manner so that it may be easily and quickly manipulated for opening or closing as desired.

Another object of the invention is to provide a clamp of the character stated which is adapted to be applied or secured to the usual apertured metal band which encircles and engages the periphery of the pad carrying board of the pressing machine head.

The invention will be best understood from a consideration of the following detailed description taken in connection with the accompanying drawings forming a part of the specification, with the understanding, however, that the invention is not to be understood as limited to the exact details of construction shown and described since obvious modifications will occur to a person skilled in the art.

In the drawing:

Figure 1 is a view in side elevation of a portion of a pressing machine head showing mounted thereon a cloth securing clamp constructed in accordance with the present invention, the cloth being removed or broken away from its position over the clamp and the band to more clearly show the structure of the invention.

Figure 2 is a sectional view taken substantially on the line 2—2 of Figure 1 showing the cloth secured in position.

Figure 3 is a sectional view corresponding to Figure 2 but showing the cloth securing band open and the edge of the cloth partly encircling the holding jaw of the clamp.

Figure 4 is a view looking at the clamp from the outer side with the movable jaw broken away to show the shiftable hinge plate attached to the body plate of the clamp.

2

Referring now more particularly to the drawing the numeral 10 generally designates a portion of the movable top or head part of a pressing machine which part includes a solid body or board 11 upon the underside of which is secured the press pad 12.

The numeral 13 generally designates a metal band which is placed around the edge of the board body 11 and secured thereto and to which band are secured a number of the cloth holding or clamping members such as constitute the present invention. One only of such clamping members is here illustrated and generally designated 14 but it will be understood by those versed in the art that a number of such cloth clamps or securing devices will be mounted upon the metal band 13 around the periphery of the board 11, use being made for mounting the clamps, of apertures 15 which are formed in the band 13 at closely spaced intervals as shown in Figures 1 and 4.

The cover clip or clamp 14 comprises a body plate 16 which is designed to be positioned vertically across the outer side of the press band 13, in the manner shown most clearly in Figures 2 and 3. This body plate has a portion of its bottom edge turned up to form the flange 17 and the lower edge of the band 13 is tightly held between this flange and the outer side of the body plate.

A portion of the top end of the body plate 16 is turned in opposed relation with the flange 17, to engage over the top edge of the band as shown in Figures 2 and 3, this flange 18 projecting inwardly and downwardly as shown to form a fixed jaw with which the hereinafter described movable jaw cooperates to hold the edge of the cover cloth 19 in position. This cover cloth is drawn tightly across the face of the pad 12 and the edge of the cloth is pulled up across the edge of the pad and of the body 11 and drawn inwardly, in the manner hereinafter described, so that the cloth will be tightly maintained in position. Maintenance of the cloth tightly in such position is accomplished by the clamps or clips forming the present invention.

The body plate is disposed against the band 13 to cover one of the openings 15 and the body plate is provided with an opening 20 through which is passed a securing element, here shown as in the form of a rivet 21, the head portion 22 of such rivet being disposed at the outer side of the body plate while the split shank of the rivet passes inwardly through the aperture 15 of the band and the two portions of the shank are turned over to engage the inner side of the band and thus maintain the rivet in place.

The holding or securing element 21 maintains in position against the outer face of the body plate 16, a hinge plate 23. This hinge plate lies between the two side flanges or wings 24 which form an integral part of the body plate and ex-

tend the full length of the same and also project outwardly therefrom.

The hinge plate 23 is provided with the relatively long slot 25 through which the shank of the holding element extends. As shown the head 22 of the rivet engages the outer face of the hinge plate to maintain the plate on the shank of the holding element or rivet whereby the plate, being confined between the flanges 24, is permitted limited up and down movement.

The lower edge of the hinge plate is provided with the central recess 26 and the portion of the plate at each side of this recess is rolled to form a hinge knuckle 27.

The numeral 28 designates the movable or swingable jaw plate, the central part of the bottom edge of which is formed to provide a hinge sleeve 29 which positions within the recess 26 between the knuckles 27. Housed within the sleeve 29 is a coil or twist spring 30 and passing through this spring and through the knuckles 27 is a pintle 31 about which the movable plate 28 swings. As shown in Figure 4 one end of the spring 30 engages at 32 against the forward or outer face of the hinge plate 23 while the other end of the spring engages as indicated at 33, against the inner side of the movable jaw plate 28. The spring 30, tending to unwind or untwist, accordingly applies opposing thrust against the plates 23 and 28 thereby tending to swing the plate 28 outwardly and downwardly.

The outer end of the plate 28 has the inturned jaw portion 34 which terminates in the rolled under lip 35. This jaw 34 is designed to extend across the jaw flange 18 and the lip 35 is designed to engage against the underside of the flange 18 at its inner edge so as to grip between the jaw flange 18 and the jaw lip 35 the edge of the cover cloth 19 as illustrated in Figure 2.

The movable parts of the clasp are proportioned with respect to the fixed plate 16 so that when the clasp is closed and the lip 35 is engaged under the jaw flange 18, the hinge plate 16 will be at the limit of its movement downwardly on the securing element or rivet 21. Also the spring 30 will be more strongly twisted and under high tension. In order to release the clasp and the cloth or release the plate 28 so that the cloth may be removed, it is necessary first to force the top part of the movable plate 28 inwardly slightly to clear the lip 35 from the inner edge of the jaw flange 18. The movable plate 28 is then shifted vertically slightly, causing a corresponding shifting of the hinge plate 23, so as to raise the jaw 34 and the lip 35 to an elevation where the plate 28 can be swung outwardly and the jaw and lip moved across the top of the flange 18. It will be readily apparent that this outward swinging of the plate 28 will be assisted by the spring 30 tending to untwist and accordingly when the clasp or cloth securing device is open it will be in the position shown in Figure 3.

To resecure the clasp to grip the free edge of the cover cloth 19, the edge of the cloth is drawn across the top of the jaw 34 and around across the free edge of the lip 35. The plate 28 is then swung upwardly from the position shown in Figure 3 and at the same time an upward pull is applied to shift the hinge plate 23 to the limit of its upward movement so that the jaw 34 and lip 35 can swing across the top of the flange 18 and when the lip 35 is in the position illustrated by broken lines in Figure 3, the plate 28 is then shifted or forced downwardly so that the inner edge of the lip 35 is below the edge of the jaw

flange 18. By releasing the plate 28 the spring will then tend to swing it outwardly thereby forcing the edge of the lip 35 under the flange 18 and securing the edge of the cloth.

From the foregoing it will be readily apparent that the clamp herein disclosed is of relatively simple construction and may be easily and quickly secured or released. At the same time the construction of the clasp is such that when it is secured it cannot be accidentally unsecured because of the fact that two separate and distinct shifting movements of the jaw plate 28 are required and such movements can only be brought about by intentionally grasping the jaw plate 28 with the hand and imparting such movements thereto.

I claim:

1. A clasp of the character described, comprising a fixed plate having a jaw flange along one end edge and projecting from one side face of the plate, a hinge plate positioned against the other side face of the fixed plate, means holding the hinge plate to the fixed plate for limited rectilinear movement thereon, a jaw plate, a hinge connection between an end edge of the jaw plate and the hinge plate adjacent to the other end of the fixed plate, a jaw formed across the opposite end edge of the jaw plate and adapted to move across the jaw flange when the jaw plate is swung toward the fixed plate when said hinge plate has been moved in one direction to a predetermined position, the jaw plate when in the last named position having the hinge plate between it and the fixed plate, the jaw and jaw flange being locked together upon reverse movement of the jaw plate after the jaw has been moved as stated across the jaw flange.

2. A cloth securing clasp adapted to be mounted upon an ironing machine press head, comprising a body plate adapted to be fixed in vertical position to the press head, a jaw flange forming an integral part of the top edge of the body plate and projecting inwardly toward the adjacent head, a hinge plate positioned against the outer side of the fixed plate, means securing the hinge plate to the fixed plate whereby the hinge plate has limited up and down movement on the fixed plate, a jaw plate secured at one end edge to the hinge plate, the opposite end edge of the jaw plate being formed to provide a jaw member, said jaw plate when swung upwardly and inwardly toward the fixed plate having its jaw member extended across the jaw flange, when the hinge plate has been shifted to a predetermined position in one direction and the jaw member engaging across the inner edge of the jaw flange when the hinge plate and jaw plate are reversely shifted.

3. A clasp of the character stated in claim 2, with spring means connected between the hinge plate and the jaw plate and tensioned to normally urge the jaw plate to swing outwardly away from the hinge and body plates.

4. A cloth securing clasp adapted to be secured to an edge of a pressing machine press head, comprising a normally vertically positioned body plate adapted to be secured to the edge of the press head, an inwardly and downwardly inclined flange integral with the top edge of the body plate and constituting a fixed jaw, a securing element carried by the body plate and projecting outwardly and having a head upon its outer end, a hinge plate positioned against the outer side of the body plate, the hinge plate having an elongated slot through which the securing element

passes, the head of the securing element being positioned against the outer side of the hinge plate whereby the hinge plate is permitted limited up and down movement with respect to the body plate, a relatively long jaw plate, hinge coupling means between an end edge of the jaw plate and the bottom edge of the hinge plate facilitating swinging the jaw plate upwardly and inwardly toward the body plate, a jaw member formed across the opposite end of the jaw plate and designed for extension across said jaw flange when the hinge plate is shifted upwardly to a predetermined position, and a turned under lip forming an integral part of said jaw member and adapted for engagement with the underside of the jaw flange when the jaw plate and hinge plate are reversely shifted after the jaw member is disposed across the jaw flange.

5. A clasp of the character stated in claim 4,

with a spring element coupling the jaw plate and hinge plate together at said hinge connecting means and normally urging oscillation of the jaw plate away from the hinge plate.
